UNITED STATES PATENT OFFICE.

WILLIAM A. WRIGHT, OF CENTRETON, NEW JERSEY, ASSIGNOR TO GEORGE R. FAGAN, OF PHILADELPHIA, PENNSYLVANIA.

MACHINE FOR SHAVING AND CUTTING STEREOTYPE AND OTHER PLATES.

SPECIFICATION forming part of Letters Patent No. 224,755, dated February 17, 1880.

Application filed December 9, 1879.

To all whom it may concern:

Be it known that I, WILLIAM A. WRIGHT, of Centreton, in the State of New Jersey, have invented a new and useful Improvement 5 in Apparatus for Shaving and Cutting Stereotype and other Plates, Printers' Leads, and other Furniture, &c., which improvement is fully set forth in the following specification and accompanying drawings, in which—

10 Figure 1 is a top or plan view of the apparatus embodying my invention. Fig. 2 is a central longitudinal vertical section thereof in line xx , Fig. 1. Fig. 3 is an end view, partly sectional.

15 Similar letters of reference indicate corresponding parts in the several figures.

My invention consists in a carriage mounted on a suitable table and supporting an adjustable blade, whereby, when plates, slugs, leads, &c., are placed on the table the blade may be 20 moved thereover, and thus shave or cut their faces true and uniform, and to any desired extent.

It also consists in suspending the blade on 25 flexible arms, whereby there is no outward strain on the blade.

It also consists in connecting the blade-supporting arms independently of each other to adjustable collars, so that either side of 30 the blade may be adjusted with the greatest nicety.

Referring to the drawings, A represents a flat-top table, supported on suitable feet or legs; and B represents a carriage, which is fitted to said table so as to have a longitudinal sliding motion thereon, said motion being imparted in the present case by rack-bars a , connected to the carriage and meshing with pinions b , whose shaft b' is mounted on the 35 table A, and provided with a suitable power or crank wheel, as at c.

From the forward end of the carriage B rises a head, C, to which is connected, by means of screw-bolts d , an upright cutter or blade, D, 40 said bolts d passing through slots e into the head, whereby the blade is vertically adjustable, so as to shave or cut a greater or less extent. Attached to the blade at opposite sides are arms E, whose upper ends are pivoted to 45 collars F, which are connected to a shaft, G,

mounted on lugs or bosses H, which rise from the head C. To the shaft G is also connected an arm or lever, J, which is conveniently accessible from the front end of the apparatus, and provided with an index, f, which sweeps 55 over a graduated arc, g, on the face of one of the lugs H.

The collars F are adjustably connected to the shaft G by means of set-screws h , and thus are independent of each other, and the arm or 60 lever J may be fixed to said shaft G in any suitable manner.

The arms E are flexible and preferably formed of spring metal.

The operation is as follows: The plate, lead, 65 or other piece or article to be shaved or cut on its face is placed on the bed or table A against the abutment A', and the knife D properly adjusted by raising or lowering the lever J until the index f sets at the graduation g, which 70 corresponds with the depth of shaving or cutting to be accomplished. The bolts or screws d are then tightened, so that the knife retains its adjusted position. The carriage is then advanced by operation of the power or crank 75 wheel c, and the knife acts on the surface of the piece or article beneath it, thus shaving or cutting it as desired or required. The carriage is then run back, and the piece or article turned and reapplied to the table A, so 80 that another side thereof is presented or a fresh piece or article is applied, and the carriage again advanced until the work is completed.

Owing to the flexible arms E, which are connected to the knife or blade D, there is no rearward or forward strain on the top of the latter, and thus the knife is not liable to be shifted from its adjusted position.

As the collars F are movable on the shaft 90 G independent of each other, either side of the blade D may be raised and lowered, whereby the adjustment of the knife may be accomplished with the greatest nicety and accuracy.

The shavings and cuttings may fall from the 95 table and drop into a box or other receptacle suitably applied.

Having thus described my invention, what I claim as new, and desire to secure by Letters Patent, is—

1. The carriage B, with the blade D suspended from the adjusting-shaft G, substantially as and for the purpose set forth.
2. The carriage B and the head C, having 5 bosses H, with graduations g, in combination with the shaft G, lever J, with index f, the blade D, and connecting-arms, substantially as and for the purpose set forth.
3. The shaft G and blade D, in combination 10 with flexible connecting-arms E, substantially as and for the purpose set forth.
4. The shaft G, blade D, and connecting-

arms, in combination with the adjusting-collars F, independent of each other, substantially as and for the purpose set forth. 15

5. The carriage B, with head C, the blade D, shaft G, collars F, and lever J, combined and operating substantially as and for the purpose set forth.

WM. A. WRIGHT.
